MOTION LAMP

Frank G. Tompsett, Omaha, Nebr.

Application August 25, 1934, Serial No. 741,460

1 Claim. (Cl. 40—40)

My present invention relates to a motion lamp having a number of novel features.

It is the purpose of my invention to provide such a lamp, having means whereby the appearance of motion may be produced on an outer, usually cylindrical, screen, and particularly to provide means whereby the artistic effect of the picture on the screen may be heightened.

In this connection, it is my purpose to provide 10 part of a scene or picture on the inside of a screen, so that the outer picture may not appear crowded when the lamp is not lighted, and yet will give the appearance of depth or effect of additional parts or figures when the lamp is lighted.

15 It is also my purpose in this connection to provide means for giving certain color effects on the outside regardless of the coloring on the light bulb, by providing certain coloring on the inside of the outer screen and also by providing proper 20 coloring on a rotary screen.

Another purpose is to provide in such a lamp a combination including a bulb with substantially upright filaments for enhancing the effect of up-and-down movement on the outer screen.

25 Still another purpose is to provide novel means for supporting a pivot jewel on a lamp bulb.

With these and other objects in view, my invention consists in the construction, arrangement and combination of the various parts of my 30 motion lamp, whereby the objects contemplated are attained, as hereinafter more fully set forth, pointed out in my claim, and illustrated in the accompanying drawing, in which:

Figure 1 is a perspective view of the complete 35 lamp embodying my invention.

Figure 2 is a vertical, sectional view of the same.

Figure 3 is a plan view, partly broken away of the outer face of the outer screen with a plan 40 view partly broken away of part of the inner face of said screen at one stage in the completion thereof, and still another plan view of a part of the inner face of the screen completed.

Figure 4 is a view similar to Figure 3 illustrating another type of design on the screen.

Figure 5 is an elevation, parts being broken away, illustrating the rotary screen mounted on the bulb, having a color design thereon for use with the screen shown in Figure 4.

50 Figure 6 is a side elevation, partly broken away, of a vertically elongated lamp with upright filaments; and

Figure 7 is a side elevation of the means for supporting the jewel on a bulb.

55 I shall first describe the lamp in a general way,

so that its parts may be readily understood, and shall then refer to those features, which have to do with my present invention.

My improved lamp includes a base, indicated by the reference numeral 10, which is preferably of 5 light weight metal, so shaped and formed as to keep down the shipping weight, and made in any suitable artistic design adapted to support a lamp, having an outer, cylindrical screen.

The base 10 has at its upper periphery an up-standing flange 11, just below which is an inwardly projecting flange or shelf 12 to support the outer screen hereinafter described. The base 10 is substantially an annular member.

Projecting inwardly from the base is an arm 15 or the like 13, which at its inner end supports an ordinary lamp socket 14, which is of the usual type, internally threaded, provided with contact means connected with a two wire insulated cable 15.

20 I employ ordinarily a round, electric light bulb 16, of clear transparent glass. The translucent stripes may be painted on the clear bulb or the whole bulb may be painted or otherwise translucently colored, and part of the coloring may 25 then be removed by scraping or otherwise to form the vertical clear stripes as shown.

20 On the bulb is mounted the jewel support 18, hereinafter more fully referred to, having projecting upwardly from the center of the top of 30 the bulb a sharp, pointed, pin-like member 19. The pin-like member 19 forms a pivot for a jewel 20 of glass or the like, which is somewhat bell-shaped, being hollow underneath, and having at its lower, outer periphery a narrow flange 21.

35 Supported on the jewel 20 is a rotary screen 22 comprising a cylindrical member of transparent or translucent material, such for instance as the commercial products known as Kotapack, Cellophane, celluloid or the like. The cylinder of the 40 screen 22 has at the bottom, a thin sheet metal reinforcing, comprising the annular ring 23 with the in-turned flange 24 at its lower edge. This ring also provides sufficient weight to balance and center the rotary screen. At the top of the screen 45 cylinder 22 is a cap 25, having the down-turned flange 26. The ring 23 and the flange 26 may be fastened to the material of the cylinder 22 by punching the ring and flange inwardly and by bending the material for gripping the cylinder, 50 as illustrated at 27 in Figure 2. That is to say, the material is punched so as to force part of it inwardly. The edge of the inwardly extending material is then bent, as by a riveting operation to properly engage the screen and cylinder.

The cap 25 has the central opening 28 to receive the jewel 20 and the material of the cap around this opening rests on the flange 21.

The cap 25 also has a series of radial openings 5 29 with upwardly inclined plates 30 to form a fan, with blades to be engaged by the upwardly moving current of heated air, for thus causing the rotary screen to rotate on the pivot pin 19.

The screen may be of transparent, semi-transparent or translucent material, and preferably has the diagonal stripes 31 painted or made of opaque or translucent material, which, however, is less transparent than the screen itself.

I provide an outer, cylindrical screen 32 set on 15 the flange 12, which is also of transparent, semi-transparent or translucent material. It may be of Cellophane, celluloid, glass or any material adapted for the purpose. This screen will be further referred to later in this description.

20 A dome-like cap 33 rests on the screen 32 and has the peripheral, down-turned flange 34. It is also provided with the air vents 35.

Outer screen

25 The outer screen 32 has a picture or scene indicated at 36. The representation of a scene on the screen 32 is omitted from Figure 2 to avoid confusion. The screen of Figures 1 and 3 has a picture or scene 36 representing a forest fire. 30 This may be applied by means of paint, printing, lithographing or otherwise, and is preferably partially opaque and partly translucent. This picture may be of any subject adapted for motion effects.

35 I have found that a problem arises in connection with these translucent screens due to the fact that when a lamp is not lighted, a more attractive scene is secured by not crowding the picture too much. On the other hand when the 40 lamp is lighted, an effect of distance or perspective may be secured in certain ways. One of these ways is to apply additional features of the scene or picture to the inside of the screen 32. Thus in Figure 3, the left-hand picture shows a part of the outer face of the screen with the forest fire scene thereon. The middle view shows a part of the inside screen with rather rough, diagonal lines 37, painted or otherwise colored red. This helps to give the fire effect. I find also that by 45 further painting or otherwise coloring parts of the inside of the screen 32, as with black paint or other coloring material 38 as shown, a better background is secured when the lamp is lighted, and by adding certain, upright, dark lines or parts 50 or figures as at 39, there is given the appearance of more trees when the lamp is lighted, and I also thus secure the effect of distance with the 55 dim outlines of trees in perspective. Thus on the inside of the screen 32 are some clear spaces, some red spaces and some dark spaces, in the instance referred to.

The resulting forest fire scene is made much more effective.

It will, of course, be understood that if other 60 than the forest fire scene were used, then the color and arrangement of the lines 37 might be changed, and the color and arrangement of the colored parts shown in the right-hand view of Figure 3 might be changed from those here 65 described.

In Figure 4, I have shown three views of another scene on a screen 32a similar to the screen 32. The left-hand view shows a part of the outer face of the screen representing Niagara Falls.

75 In the middle view of Figure 4, I have shown a

portion of the inside of the screen with a dark background 40, and with dark lines 41, for example, to enhance the appearance of falling water. In the right-hand view of Figure 4, I have shown the Falls part of the picture with other 5 translucent coloring material, preferably green, as indicated at 42, for further giving the greenish tinge to the falling water.

I find that the use of the dark background and the green coloring for the Falls helps to eliminate any showing of red in the Falls scene. This result is still further improved by using on the rotary screen 22a, similar to the screen 22, diagonal stripes 43, preferably of translucent character and green color.

10 It will, of course, be understood that the additional figures 39 in the form of the device illustrated in Figure 2 must be properly located, shaded and shaped with relation to the scene shown on the outside of the screen, in order to 15 get the most artistic results. The same is true of the background and coloring on the inside of the screen for the screens of Figures 3 and 4, and also of the black stripes and green coloring of the screen of Figure 4.

Bulb

For economy of manufacture, I preferably use for all of my lamps a round bulb, colored red with clear up and down stripes, such as the bulb 20 illustrated in Figure 2 and also in Figure 5. With the background and green coloring as illustrated in Figure 4, I can continue to use the red bulb without getting much, if any red, in the finished Falls scene when the lamp is lighted.

35 It will, of course, be understood that any preferred color or combination of colors may be used on the bulb.

These bulbs are ordinarily of the type having the substantially horizontal film.

40 I find that I can further enhance the effect of water falling vertically, by using a vertical, elongated bulb 16a, such as that illustrated in Figure 6, provided with the substantially upright filament 44. With the upright filament, the appearance of up and down motion is more easily produced.

I have found it quite a problem to properly and economically support the rotary screen 22 on the bulb and to provide a suitable bearing for 50 the rotary screen, so that the upwardly moving current of air will always and certainly effect the rotation of that screen. The support 18 above referred to affords very excellent means for securing the desirable results. This 55 support is made originally in the form of a broken ring of resilient wire. The ends are then forced apart until the wire takes on a somewhat spiral appearance, whereupon it can be resiliently snapped on the bulb and will hold its position.

60 It will, of course, be understood that the pivot 19 is added to the holder before the holder is placed on the bulb. The length and size of the resilient wire of the holder 18 depends upon 65 the type and size of bulb with which it is to be used.

In Figure 6, I have shown a modified form 70 18a of this holder made of such size and shape as to fit an upright bulb of relative small diameter, whereas in Figures 2 and 7, the holder is shown of such size and shape as to fit on a round bulb.

75 It will readily be seen from the foregoing that numerous variations may be made in the de-

tails of the structure of my improved motion lamp. Any materials suitable for the purpose may, of course, be employed. It is therefore my purpose to cover by my claims any different materials, changes in structure or arrangement of parts, which may come reasonably within the scope of my invention and be distinguished from the prior art.

I claim as my invention:

- 5 10 In a lamp structure for giving the illusion of a forest fire, a base, a light source thereon, an inner rotary screen having markings thereon,

and an outer translucent surrounding screen, having a forest fire scene on its outer surface, showing trees, and having on its inner surface substantially vertical dark parts, staggered with relation to the showing of trees on the outer 5 surface, so that when the lamp is not lighted, the trees will not seem crowded in the visible scene, whereas when the lamp is lighted the dark parts will give the appearance of additional trees in the distance.

10
